CLAIM

The ornamental design for a mounting device for a wireless integrated circuit chip module, as shown and described.

DESCRIPTION

FIG. 1 is first perspective view of the mounting device for a wireless integrated circuit chip module according to our new design.

FIG. 2 is a second perspective view of the mounting device for a wireless integrated circuit chip module.

FIG. 3 is a third perspective view of the mounting device for a wireless integrated circuit chip module.

FIG. 4 is a fourth perspective view of the mounting device for a wireless integrated circuit chip module.

FIG. 5 is a front view of the mounting device for a wireless integrated circuit chip module.

FIG. 6 is a rear view of the mounting device for a wireless integrated circuit chip module.

FIG. 7 is a right side view of the mounting device for a wireless integrated circuit chip module.

FIG. 8 is a left side view of the mounting device for a wireless integrated circuit chip module.

FIG. 9 is a top view of the mounting device for a wireless integrated circuit chip module; and,

FIG. 10 is a bottom view of the mounting device for a wireless integrated circuit chip module.
